United States Patent Office

Des. 208,930
Patented Oct. 17, 1967

208,930

TIMER OR SIMILAR ARTICLE

Carl N. Johnson, Stratford, and William V. Judson, Westport, Conn., assignors to General Electric Company, a corporation of New York

Filed June 2, 1966, Ser. No. 2,519

Term of patent 14 years

(Cl. D42—7)

FIG. 1

FIG. 3

FIG. 2

FIG. 5

FIG. 6

FIG. 1 is a front perspective view of a timer embodying our new design;

FIG. 2 is a bottom plan view thereof;

FIG. 3 is a front elevational view thereof;

FIG. 4 is a side elevational view thereof;

FIG. 5 is a rear elevational view thereof; and

FIG. 6 is a top plan view thereof.

The stippled texture extends continuously over the top and sides of the article.

The dominant features of our design reside in those portions shown in full lines.

We claim:

The ornamental design for a timer or similar article, substantially as shown and described.
